ATTORNEY

UNITED STATES PATENT OFFICE.

JAMES F. WILLIAMS AND CHARLES MUSTIN, OF VINCENNES, INDIANA,
ASSIGNORS OF ONE-HALF TO FRANCIS SCHENKER, OF VINCENNES,
INDIANA.

ATTACHMENT FOR TROUSERS.

SPECIFICATION forming part of Letters Patent No. 719,965, dated February 3, 1903.

Application filed July 14, 1902. Serial No. 115,395. (No model.)

To all whom it may concern:

Be it known that we, JAMES F. WILLIAMS and CHARLES MUSTIN, of Vincennes, county of Knox, and State of Indiana, have invented 5
a certain new and useful Attachment for Trou-
sers; and we do hereby declare that the follow-
ing is a full, clear, and exact description there-
of, reference being had to the accompanying
drawings, in which like numerals refer to like
parts.

The object of this invention is to provide a
simple means to hold the upper part or waist
of trousers open when not in use, to enable a
man to put them on in the least possible time,
15 and to close and fasten them rapidly and se-
curely. It is especially advantageous for fire-
men and others in like positions of duty.

The full nature of the invention will be un-
derstood from the accompanying drawings
20 and the following description and claims.

In the drawings, Figure 1 is an elevation
of the front upper portion of a pair of trousers
with the device in place and the waist of the
trousers open. Fig. 2 is a plan view of the
25 attachment by itself. Fig. 3 is an inside
elevation of a portion of the attachment in-
verted. Fig. 4 is a vertical section of the de-
vice in the position shown in Fig. 3 on the
30 line 4 4 of said figure. Fig. 5 is a detailed
view of a portion of the device in its upright
position, with parts broken away and in sec-
tion to show the pawl construction. Fig. 6
is a vertical section of the device on the line
35 6 6 of Fig. 5.

Referring now to the details of what is
shown in the drawings, 10 represents the up-
per part of a pair of trousers. The attach-
ment constituting this invention is secured
40 by threads or stitching 11 to the waistband
of the trousers, so as to be held permanently.

The attachment consists of a metal casing
or guide 12, formed with a curve, so as to con-
form substantially to the waist. The strip 13
45 is formed of metal with a similar curvature
and is slidable in the casing. The casing is
provided with perforated lips 14, whereby it
is stitched to the waist of the trousers. At
the front end of the casing a perforated lip 15
is turned inward and backward, as shown,
50 whereby it can be secured on the inside of

the waistband of the trousers by stitches.
In the construction shown in the drawings
this lip 15 is a plate extended from a box-like
enlargement 17, secured on the front end of
the casing 12. The outer wall of the casing 55
12 has a bead 18 to form a longitudinal-ex-
tending groove. The strip 13 is provided at
its inner end with a stud or pin 20, that
moves in said grooveway 18. This grooveway
does not extend entirely to the front end of 60
the casing 12, but, as shown, nearly to the
box-like enlargement 17, so that at the termi-
nation of the grooveway the wall of the cas-
ing 12 serves as a stop to engage the stud
20 and limit the outward movement of the 65
strip 13, so as to prevent its entire removal.
Said strip has at its outer end an inturned
perforated lip 21, whereby it is secured by
stitches to the other side of the trousers oppo-
site to the side to which the casing is secured. 70
Preferably the casing is secured to the left
side and the plate to the right. The trousers
are therefore closed by pushing the strip 13
from the position shown in Fig. 1 into the cas-
ing 12 as far as it will go. The turned outer 75
end of the strip will move to the right, as shown
in Fig. 2, until it abuts against the curved por-
tion of the lip 15 and will bring the two ends of
the waistband of the trousers snugly together.
The trousers are held closed by the pawl 23 80
engaging teeth or rack 24 on the upper edge
of the strip 13, as appears plainly in Fig. 5.
The pawl there extends through an opening
in the top of the box-like construction 17 and
is pivoted to its side walls by the pin 25, so 85
that its inner end will engage the teeth 24 of
the rack when pushed down by the flat spring
26. The trousers are opened by bearing
down on the outer end of the pawl 25, and
thus releasing it from the teeth 24 of the rack, 90
then drawing the strip 13 outward. It is
therefore seen that with this attachment to
trousers they can be held when not in use
with the top open, as shown in Fig. 1, where-
by they can quickly be put on. When put 95
on, they can quickly be closed by merely
pushing in the strip 13 to its limit, and the
pawl 23 will automatically lock the strip 13 in
its inward position.

It is observed that the metal casing 12 ex- 100

tends only to one front edge of the trousers and the notches on the strip 13 extend to the other front edge, so that the two front edges of the trousers may be brought up against each other.

What we claim as our invention, and desire to secure by Letters Patent, is—

1. The combination with a pair of trousers, of a longitudinally-extending metal casing secured to the waistband on one side of the trousers and extending to one front edge thereof, a metal strip longitudinally slidable in said casing and secured at its outer end to the waistband on the other side of the trousers at the front, means for preventing the complete withdrawal of said strip from said casing, and means for locking the plate in said casing.

2. The combination with a pair of trousers, of a metal casing secured on one side of the trousers and extending to one front edge thereof, a metal strip longitudinally slidable in said casing and secured at its outer end to the other front edge of the trousers, and means for locking said strip in said casing whereby the front edges of the trousers may be brought together and held in such position.

3. An attachment for trousers comprising a casing, perforated lips connected therewith for securing it to the waistband of the trousers, a longitudinally-extending grooveway in the wall of said casing that terminates before reaching the end thereof, a box-like construction secured to the front end of the casing, a metal strip longitudinally slidable in said casing with one edge toothed, means on the outer end of said strip for securing it to the waistband of the trousers, a pin on said strip within said casing that moves in said grooveway for preventing the complete withdrawal of said strip, a pawl pivotally mounted in said box-like construction with one end extending outward, and a spring for holding the outer end of said pawl in engagement with the teeth of said strip.

In witness whereof we have hereunto affixed our signatures in the presence of the witnesses herein named.

JAMES F. WILLIAMS.
CHARLES MUSTIN.
